UNITED STATES PATENT OFFICE

FRANK A. RANTZ, OF ST. PETERSBURG, FLORIDA

GARAGE DOOR

Application filed July 5, 1927. Serial No. 203,576.

This invention relates to garage doors and more particularly to a means for securing the door in either open or closed position.

An important object of the invention is to provide a device of this character for use with swinging garage doors of such construction that the operation of one of the doors will cause simultaneous operation of the other door and the doors will be automatically latched when they reach their open position.

A further object of the invention is to produce a device of this character which will be extremely simple in its construction and operation, will be very durable and efficient in service and which may be readily adjusted to secure the doors in the proper position when opened.

These and other objects I attain by the construction shown in the accompanying drawings, wherein for the purpose of illustration is shown a preferred embodiment of my invention and wherein:

Figure 1 is a detail sectional view through a building, the doors of which are equipped with control mechanism constructed in accordance with my invention showing the arrangement where the doors are to be opened to an equal extent;

Figure 2 is a similar view illustrating the slight changes necessary where the doors are to be unequally opened;

Figure 3 is an enlarged detail sectional view on the line 3—3 of Figure 1;

Figure 4 is a side elevation partially in section of the adjustable stop and latch for checking movement of the door to closed position and holding the same therein;

Figure 5 is a section on the line 5—5 of Figure 3.

Referring now more particularly to the drawings, the numeral 10 generally designates the door frame of a garage door, to the upper member of which I secure the forward end of a channel member 11 extending horizontally into the garage from the door frame and having its rear end secured to the roof (not herein shown) by a suitable support 12. The channel of the member 11 is downwardly directed and the member 11 is slidably embraced by a yoke 13, the under face wall 14

of which has directed therethrough a bolt 15, the head of which operates in the channel 16 and the shank of which projects below the lower face of the yoke and provides a pivot for the inner ends of a pair of rigid links 17, 55 the outer ends of which are pivotally connected with brackets 18 secured to the doors 19.

It will be obvious that by varying the length of the links 17, the doors 19 which are hinged at their outer edges to the frame may be caused to assume a desired open position and both doors may be opened to the same extent or one door opened to a certain degree and the other door opened to a greater or less 65 degree.

Secured to the channel member adjacent the forward end thereof is a stop 20 comprising a metal plate secured to the channel member by a bolt 21 directed therethrough. 70 This same bolt screws to the upper surface of the channel member one leaf 22 of a hinge, the other leaf 23 of which has secured thereto a plate 24, the rear end of which is downbent to form a hook 25, the bill of which normally rests upon the upper surface of the channel member and the rear face of which forms a cam for engagement by the forward end of the yoke 13, so that the yoke may lift the same and pass under the hook 80 to engage the stop 20. When the stop is engaged, the hook will again fall into engagement with the upper surface of the channel beam and will prevent return movement of the yoke, locking the doors in their open position. To provide a release for this latch, the plate at the opposite side of the hinge from the hook 25 is formed with an operating arm 26 with which may be engaged a flexible element 28 led to any convenient 85 point.

Adjustably secured to the channel member adjacent the rear end thereof is a second stop 27. The stop 27 comprises two plates 28 and 29 connected by bolts 30 passing therethrough at opposite sides of the channel member. Clamped between the upper plate and the base or upper wall of the channel member 11 is one leaf 31 of a hinge, the end of which is hooked, as at 32, to prevent its displacement.

- ment. The second leaf 33 of the hinge has secured thereto a plate 34 exactly similar to the plate 24, with the exception of the fact that the hook 35 thereof has its bill at its forward end and the arm 36 at the opposite end is preferably downturned instead of upturned as is the case with the arm 26. A flexible element 37 is connected to the arm 36 for operation thereof.
- 10 It will be obvious that with a structure of this character, means are provided for positively limiting the door in its movement both to open and closed positions and to lock the door in each of these positions.
- 15 Since the stops serve to positively limit movement of the door, the channel member through these stops will take up a great portion of the shock to which the hinges and stops of the door frame are subjected in the
- 20 usual rough handling which garage doors receive. It will also be obvious that a structure of this character may be both cheaply manufactured and installed and will be very durable and efficient in service.
- 25 Since the construction hereinbefore set forth is capable of a certain range of change and modification without materially departing from the spirit of the invention, I do not limit myself to such specific structure except as hereinafter claimed.

I claim:—

The combination with a horizontal support and a yoke slideable thereupon, of latch means adjustably mounted on said support and 35 adapted for engagement with said yoke, said latch comprising a fixed leaf adjustably mounted on said horizontal support, a rockable leaf pivotally mounted on said fixed leaf, and yoke engaging means mounted on said 40 pivoted leaf, said yoke engaging means comprising an elongated plate having a reverted forward end portion adapted for engagement with one end of said yoke, an angularly inclined rear portion adapted for engagement 45 with an operating element.

In testimony whereof I hereunto affix my signature.

FRANK A. RANTZ.
